UNITED STATES PATENT OFFICE.

WILLIAM ALLEN PENFIELD, OF MERIDEN, CONNECTICUT, ASSIGNOR TO THE BRADLEY & HUBBARD MFG. CO., OF MERIDEN, CONNECTICUT, A CORPORATION.

WICK-RAISER FOR CENTRAL-DRAFT LAMPS.

SPECIFICATION forming part of Letters Patent No. 783,799, dated February 28, 1905.

Application filed December 30, 1904. Serial No. 238,896.

To all whom it may concern:

Be it known that I, WILLIAM ALLEN PENFIELD, a citizen of the United States, residing at Meriden, in the county of New Haven and State of Connecticut, have invented a new and useful Improvement in Wick-Raisers for Central-Draft Lamps; and I do hereby declare the following, when taken in connection with the accompanying drawings, and the figures of reference marked thereon, to be a full, clear, and exact description of the same, and which said drawings constitute part of this specification, and represent, in—

Figure 1, a side view, partially in section, of such parts of a central-draft lamp as are necessary to illustrate my improved wick-raiser; Fig. 2, a top or plan view of the same with the upper end of the wick-arresting spindle broken away; Fig. 3, a broken side view of the wick-carrier and rack connected therewith, the upper end of the wick-tube being broken away to show the spring wick-gripping jaws and illustrating the engagement of the lug on the rack with the bridge.

This invention relates to an improvement in wick-raisers for central-draft lamps, and particularly to such as are provided with a rack and pinion for adjusting the wick, the object of the invention being a simple arrangement of parts whereby the wick-holder may be readily raised when desired to remove or adjust the wick with relation thereto and also to indicate when the wick has been burned to such an extent that adjustment is desirable; and the invention consists in the construction as hereinafter described, and particularly recited in the claims.

In carrying out my invention I employ the usual tubular wick-carrier 2, shell 3, and outer wick-tube 4, through which the wick-carrier extends. Secured to the tube 4 within the shell 3 is a bridge 5, through which the shank 6 of an adjusting-pinion 7 extends, the inner end of the shank being upset within the tube, so as to swivelly connect the same thereto. Secured to the lower end of the tube 4 is a rack 8, which extends upward through the shell 3 and bridge 5, the teeth 9

of the rack meshing with the pinion 6, so that as the pinion is turned the tube will be raised or lowered. At a predetermined point on the forward face of the rack is a lug 10, adapted to engage with the lower edge of the bridge 5, as shown in Fig. 3, and thereby arrest the upward movement of the wick. The thickness of this rack is less than the space between the bridge and the tube, and when it is desired to raise the wick-tube, so that the spring-jaws 11 thereof may be released from the wick, the rack is pressed inward toward the tube, so as to disengage the lug 10 from the lower end of the bridge and permit the same to pass upward through the bridge under the continued movement of the pinion. When raised so that the spring-arms extend above the upper end of the wick-tube, they will spring outward, thus releasing the wick and allowing it to be adjusted or removed, as desired. Upon turning the pinion the rack moves downward, turning the wick with it, and after the lug passes below the bridge the rack moves outward, so as to bring the lug into the path of the edge of the bridge and so as to act as a stop to limit the upward movement of the rack, it being understood that the rack will yield to permit it to be pressed toward the tube, although it will normally bear against the inner face of the bridge, so as to assure the lug coming in contact with the lower edge thereof. To permit the rack to have sufficient spring action, it may be reduced in thickness near its lower end, as indicated at 12 in Fig. 1.

It will thus be seen that by a very simple arrangement and without interfering with the action thereof means are provided to arrest the upward movement of the wick at a predetermined point, and yet permit the wick to be raised and released from the wick-tube when desired.

Having fully described my invention, what I claim as new, and desire to secure by Letters Patent, is—

1. A wick-raiser for central-draft lamps comprising a wick-carrier, a vertically-arranged rack connected therewith, a pinion en-

gaging with said rack, a lug on said rack, and a stop with which said lug may engage to limit the upward movement of the wick, said rack radially movable whereby it may be disengaged from said stop, substantially as described.

2. A wick-raiser for central-draft lamps comprising a wick-carrier, an outer wick-tube through which said carrier extends; a bridge secured to said tube, a vertically-arranged rack connected with the lower end of said tube and extending upward through said bridge, a

lug on said rack adapted to engage with the lower edge of said bridge, and a pinion engaging with said rack for raising and lowering the same, substantially as described. 15

In testimony whereof I have signed this specification in the presence of two subscribing witnesses.

WILLIAM ALLEN PENFIELD.
